UNITED STATES PATENT OFFICE

144,199

DESIGN FOR A COMBINED REMOVABLE SOCK AND SLIPPER

Betty Katz, New York, N. Y.

Application September 24, 1945, Serial No. 122,280

Term of patent 7 years

(Cl. D7—7)

To all whom it may concern:

Be it known that I, Betty Katz, a citizen of the United States of America, residing in New York city, county of Kings, and State of New York, have invented a new, original, and ornamental Design for a Combined Removable Sock and Slipper, of which the following is a specification, reference being had to the accompanying drawing, forming part thereof, wherein,

The figure is a front perspective view of a combined removable sock and slipper showing my new design.

I claim:

The ornamental design for a combined removable sock and slipper, substantially as shown.

BETTY KATZ.
